(57) **CLAIM**

The ornamental design for a dash cam as shown and described.

DESCRIPTION

FIG. 1 is a perspective view of a dash cam showing my new design;

FIG. 2 is another perspective view thereof;

FIG. 3 is a front view thereof;

FIG. 4 is a back view thereof;

FIG. 5 is an enlarged left view thereof;

FIG. 6 is an enlarged right view thereof;

FIG. 7 is a top plan view thereof;

FIG. 8 is a bottom plan view thereof; and,

FIG. 9 is a partial enlarged view of portion 9 in FIG. 1. The broken lines depict portions of the dash cam and form no part of the claimed design.

The dot-dash broken lines represent the designation of an enlargement view and form no part of the claim.
